UNITED STATES PATENT OFFICE

CHRISTIAN F. BATH, OF ABILENE, KANSAS

LIFTING JACK

Application filed November 1, 1927. Serial No. 230,362.

The present invention is directed to improvements in lifting jacks.

The primary object of the invention is to provide a device of this character constructed in such manner that a piano or other article of furniture can be lifted in order that floor coverings may be placed thereunder.

Another object of the invention is to provide a device of this type which is simple in construction, durable, efficient in operation and one which can be manufactured at a very small cost.

Another object of the invention is to provide a jack for this purpose which can be operated with very little effort on the part of the user and held in its operative position with ease, while the floor covering is being properly placed thereunder.

With these and other objects in view, this invention resides in the novel features of construction, formation, combination and arrangement of parts to be hereinafter more fully described, claimed and illustrated in the accompanying drawing, in which—

Figure 1 is a side elevation thereof.

Figure 2 is a view partly in elevation and partly in section.

Figure 3 is a sectional view on line 3—3 of Figure 2.

Figure 4 is a fragmentary detail vertical sectional view.

Referring to the drawing, 1 designates a base plate and 2 a pedestal, said pedestal being formed from a single strap of metal so bent as to provide spaced sides 3—3 connected at their upper ends by a top 4 having a slot 5 formed therein, the purpose of which will be later explained

The lower ends of the sides 3 terminate in horizontal flanges 5' which are secured to the base plate 1 by rivets 6.

The lifting bar 6' includes a vertically disposed shank 7 capable of sliding in the slot 5, said shank having its lower end provided

with a horizontally disposed extension 8 upon which is welded a foot plate 9. The shank 7 is provided with a vertical slot 10 for slidably engaging the cross bolt 11 supported by the sides 3—3, said bolt serving to 50 guide the lifting bar during the movement thereof. The shank has fixed thereto a round lug 12, the purpose of which will be later explained.

The sides 3—3 have their rear edges provided with rounded extensions 13 which support a bolt 14, said bolt serving as a fulcrum for the lever 15, there being a recess 16 in the lever for engaging said bolt to prevent the former from slipping when the lever is 60 rocked. Obviously the lever can be quickly disengaged from the bolt 14, when the jack is not in use.

It will be obvious that when the lever 15 is swung downwardly the lifting bar 6' and 65 the foot plate 9 will be elevated owing to the fact that the inner end of the lever engages the lug 12, and upon placing the foot plate 9 under a piano or other article the same can be conveniently lifted.

Upon reference to Figure 4 it will be observed that the shank 7 lies adjacent one of the sides 3 and the slot 5 is offset to accommodate said shank.

From the foregoing description it will be 75 seen that a jack has been provided which is extremely simple in construction and one which can be easily and quickly placed in a position to permit the foot plate 9 to engage under the article to be lifted, the construction being such that very little effort will be required to elevate the lifting bar and foot plate.

Having thus described the invention, I claim:

A lifting jack comprising a base, a pedestal consisting of a pair of spaced sides having their lower ends fixed to the base, a top connecting the upper ends of the sides and having an opening therein, a lifting bar 90

slidable in the opening and upon one of said sides to provide a space between the bar and other side, a lug fixed intermediate the ends of the bar and extending into said space, said bar having a slot therein, a bolt supported by the sides for slidably engaging the slot, a cross bolt supported by the sides, a lever removably engaged in the space and having a recess therein for pivotally and detachably 10 engaging the cross bolt.

In testimony whereof I affix my signature.
